MEANS FOR AND METHOD OF REFORMING
KNUCKLESEdmund P. Kinne, Alliance, Ohio, assignor to
American Steel Foundries, Chicago, Ill., a cor-
poration of New Jersey

Application October 19, 1931, Serial No. 569,565

16 Claims. (Cl. 78—75)

The present invention relates to knuckles and more in particular to knuckles for use in standard A. R. A. type D couplers.

Among the objects of the present invention is 5 to provide a novel means for and method of reforming knuckles for railway car couplers, as likewise the improved product formed thereby, and more particularly to a means for and method of reforming knuckles adapted for use in standard 10 A. R. A. type D couplers.

It is interesting to note that standard A. R. A. type D couplers are of a very sturdy design and the knuckles forming a part thereof, instead of breaking and being retired from service, wear 15 out less rapidly than some of the other parts. This has resulted in a vast accumulation by the railroads of a surplus supply of knuckles, which, until the present time, have not been reconditioned for use because of the expense involved 20 in reforming the same. These knuckles are worn to an extent which makes them impractical and dangerous to use because of the fact that when the same are placed in couplers, they will not give a sufficiently correct contour line to 25 meet the requirements of safety against accidental uncoupling. Various methods have been tried in an endeavor to recondition or reform these knuckles at a substantially low and economical figure as compared with the cost of new 30 knuckles, but these methods have been unsuccessful. Briefly, these methods have included forging, swaging, or more frequently by endeavoring to weld portions of material upon the worn parts. These methods are quite unsatisfactory, 35 inasmuch as in practice, these forged, swaged, or added portions of material have been unable to withstand the severe usage to which the same have been subjected.

It is therefore an object of the present invention 40 to provide novel means for reconditioning and reshaping the knuckles of car couplers and which may be easily and readily manipulated for effectively restoring the contour of worn 45 knuckles to the contour of a new knuckle, this means being inexpensive, and the cost of reforming these worn knuckles being effected at an economical figure relative to the cost of a new knuckle.

Another object of the present invention is to 50 provide a novel means for reforming and reconditioning type D knuckles which will result in the formation of a knuckle conforming to the contour of a new knuckle which will meet all the 55 requirements of safety against accidental un-

coupling, as likewise one which will meet all standards of gauge and contour.

The invention includes the idea of providing a method of reforming type D knuckles and includes the steps of heating the knuckle to a proper temperature, and applying a pressure thereto while the same is confined within certain limits defining the contour of a new knuckle, whereby the same is reshaped and reconditioned. Knuckles reformed or reconditioned in this manner are suitable for use in a new coupler or in other couplers which have not been subjected to excessive wear. It has also been found that the strength of the knuckles reformed in accordance with this procedure has not been lessened, 15 but on the other hand, has actually been increased because of the heat treatment.

With these and various other objects in view, the invention may consist of certain novel features of construction and operation, as will be 20 more fully described and particularly pointed out in the specification, drawings and claims appended hereto.

In the drawings, which illustrate an embodiment of the device, and wherein like reference 25 characters are used to designate like parts—

Figure 1 is a fragmentary view in horizontal cross section of a standard A. R. A. type D coupler with the knuckle and lock in place;

Figure 2 is a top plan view of a device made in 30 accordance with the present invention for reforming worn knuckles and disclosing the same in condition to receive a knuckle;

Figure 3 is a top plan view similar to that shown in Figure 2 of the drawings and showing 35 a knuckle held in place thereon;

Figure 4 is a view in side elevation of the device shown in Figures 2 and 3 of the drawings with the knuckle in place as in Figure 3;

Figure 5 is a view in side elevation similar to 40 Figure 4 and disclosing the device in a position after the reforming of the knuckle has been effected;

Figure 6 is a view in vertical cross section taken in the plane represented by line 6—6 of Figure 5 45 of the drawings;

Figure 7 is a view in vertical cross section taken in a plane represented by line 7—7 of Figure 3 of the drawings; and

Figure 8 is a fragmentary top plan view of a car 50 coupler disclosing the relative contour of a worn knuckle and a reformed knuckle made in accordance with the present invention.

Referring now more in detail to the drawings, a standard A. R. A. type D coupler is disclosed 55

in Figure 1 and comprises a head 2 having a knuckle 4 pivotally mounted therein, as by means of a pin 6. This knuckle 4 is formed in accordance with the standard A. R. A. type D contour 5 and includes a nose 8 and a tail portion 10 adapted to be received within the head of the coupler 2 and be locked in position by means of the lock 12, this lock being associated with the knuckle opener 18 having cooperative surface engagement 10 with the locking face 20 disposed on the tail piece 10.

Under actual operating conditions, the knuckle 4 becomes worn over the locking face 20, as likewise over the pulling surfaces 22 of the lugs 24, 15 the contacting surfaces 26 of the pin protector 28, and the contacting surfaces 30 between the knuckle 4 and the knuckle pivot pin 6, which results in a looseness of the contour of a worn knuckle thereby increasing the gauge distance G 20 between the nose 8 of the knuckle and the guard arm 32 of the coupler head. The increase in the gauge distance G is limited by standard requirements, and once this opening has increased beyond this limit, the danger of accidental uncoupling of opposing couplers is augmented and a 25 replacement thereof is necessary and required.

As hereinbefore indicated, these worn knuckles have accumulated, and even though various attempts have been made to reform the same as 30 by forging or swaging, or by adding material to the locking face 20 thereof, no successful method has been heretofore devised for economically and cheaply reconditioning these knuckles for use.

The present invention accordingly comprehends the idea of providing suitable means for reforming and reshaping these worn knuckles 4, whereby the same may be again used in a new coupler or couplers which have not been subjected to excessive wear. Such means is disclosed as comprising a movable die block or member 34 pivotally mounted, as at 36, upon the base 38, this movable die block or member 34 being provided with a recess 40 conforming substantially to the contour of the tail piece 10 of the 45 knuckle 4. A knuckle 4 to be reformed in accordance with the present disclosure is inserted within this recess or opening 40 and is secured in place, as clearly shown in Figures 4 and 6 of the drawings, by means of a pin or pivot 42 adapted 50 to extend between lugs or ears 44 and 46 provided on the upper portion of the die block 34, the same passing through openings 48 and 50 provided in these ears 44 and 46, respectively, and passing through the opening 52 which is normally 55 adapted to receive the pivot pin 6 when the knuckle is mounted within the coupler head 2.

After the knuckle 4 has been inserted within the die block 34 and secured in place by the pin 42, the tail portion thereof is firmly secured in its 60 proper position by means of the wedge blocks 54 and 56, the smaller wedge block 54 being provided with a handle 58 for inserting and removing the same from the die block 34. After these 65 wedge blocks 54 and 56 have been inserted in their respective openings provided in the die block 34, the knuckle 4 and the knuckle reforming device are in an assembled position substantially corresponding to that disclosed in Figure 4 70 of the drawings. The movable die block 34 is further provided with a substantially vertical or upright opening or cavity 59 adapted to receive a die member 60 extending upwardly from the base 38 and being provided with a recess or groove 62 75 in its upper surface corresponding substantially

to the back faces 64 and 66 of the knuckle tail piece.

Before the application of pressure to the knuckle 4, as will be later more fully disclosed, the movable die block or member 34 is normally 5 maintained in a slightly tipped position, as clearly shown in Figure 4 of the drawings, by means of coil springs 68 adapted to be positioned within the cavities or recesses 70 provided in this die block, these springs being supported upon the 10 base 38 and having their other or lower end maintained in position by means of the lugs or protuberances 72 provided on this base 38.

After the knuckle 4 has been clamped or secured in the die block 34 in the manner above 15 disclosed, the knuckle, together with the knuckle forming device, may be moved into a position whereby a die member 74 engages with the front face of the knuckle 4, as clearly shown in Figure 4 of the drawings. This die member 74 is provided with a surface portion 76 corresponding substantially with the front face of the knuckle 4 and the same is pivotally secured, as by means of the pin 78 to a bracket or arm 80 of a hydraulic press or the like (not disclosed). Before the application of pressure through the medium of the hydraulic press or the like, a die block 82 is moved into place as shown, and immediately below the nose of the knuckle.

After the die block 82 has been moved into 30 association with the nose 8 of the knuckle 4, and the knuckle, together with the knuckle forming device, has been placed in association with the die block 74 of the hydraulic press, as shown in Figure 4 of the drawings, the hydraulic press 35 or other suitable means may be operated to apply a pressure along the front face of the knuckle 4 to cause a bending of the worn knuckle along a plane represented by line A—A of Figure 1 of the drawings. The bending of this nose of 40 the knuckle 4 is limited in extent by the die block 82 which is provided with a recessed portion 84 having a surface corresponding to the contour of the nose of a new knuckle. Contact of the nose of the knuckle 4 with this surface 45 and during the application of pressure reforms the contour of the nose to correspond with the contour of a new knuckle. During the application of pressure to the front face of the knuckle 4, the die block or member 34 is moved downwardly toward the base 38 and against the spring action of the coil springs 68, whereby the surface of the recessed portion 62 engages or comes into contact with the surfaces 64 and 66 of the tail portion of the knuckle to reform the contour 55 thereof and to cause an engagement of the pulling surfaces 36 and 38 with overhanging shoulder portions 90 and 92 of the die member 34, thus 60 causing a reshaping of these pulling surfaces to correspond with the contour of the surfaces of a new knuckle. After the knuckle has been reformed or reshaped in accordance with this disclosure, the pressure may be released and the knuckle 4 removed from the die block 34 by 65 removing the wedge block 56 and the block 54, as likewise the pin 42.

As clearly shown in Figure 8 of the drawings, the contour of a knuckle which has been in use and been subjected to wear is shown at 94, whereas a knuckle which has been reformed and 70 reshaped in accordance with the present disclosure is shown as having a contour represented by the line 96. Even though substantial wear has taken place over the pulling surface 26 of the tail piece of the knuckle 4, and at other 75

bearing points, the nose 8 of the knuckle may be proportionately bent in a plane substantially represented by line A—A to position the nose 8 of the knuckle in relation to the pulling face 20 5 so that when this reformed and reshaped knuckle is used in a new coupler or a coupler which has been subject to very little wear, the gauge distance represented by the line D of Figure 8 is equal to the gauge distance G as shown in Figure 1 of a new type D coupler. This new and 10 novel method of reforming or reshaping a knuckle has the distinct advantage of providing a knuckle which may not only be used in a new coupler or one having substantially little wear, but likewise 15 may be interchangeable from one coupler to another, and still maintain the acceptable gauge distance. It has also been found that the strength of the knuckle is not impaired or lessened because of the bending or compressing of portions 20 thereof, but on the other hand is substantially increased because of the heat treatment necessary to effect this bending and compressing.

It is to be understood that I do not wish to be limited by the exact embodiment of the device 25 shown, which is merely by way of illustration and not limitation, as various and other forms of the device will of course be apparent to those skilled in the art without departing from the spirit of the invention or the scope of the claims.

30 I claim:

1. A knuckle reforming device comprising a movable die member for receiving the tail portion of said knuckle, means associated therewith and adapted to engage said tail portion upon 35 movement of said member under pressure for reshaping said tail portion to conform to the contour of a new knuckle, and means carried by said movable die member for engaging the nose of said knuckle for reforming the same.

40 2. A knuckle reforming device comprising a die for receiving and reshaping the hub and tail of said knuckle, means for supporting said knuckle whereby the nose thereof is exterior to said die and free to move relative to said tail, means 45 for applying pressure to said nose whereby the same is moved into its normal relation with said tail and said tail is reshaped to correspond to similar parts in a new knuckle, and means engageable with said nose for reforming the same 50 when said pressure is applied to correspond to similar parts of a new knuckle.

55 3. A knuckle reforming device comprising a movable die member for receiving and reshaping a hub and tail of said knuckle, means for supporting said knuckle whereby the nose thereof is exterior to said die and free to move relative to said tail, means for applying pressure to said nose whereby the same is moved into its normal relation with said tail, and means engageable 60 with said tail upon application of pressure whereby said tail and hub are reshaped to conform with certain portions of the cavity of said die member to correspond to similar parts of a new knuckle.

65 4. A knuckle reforming device comprising a movable die member for receiving and reshaping a hub and tail of said knuckle, means for supporting said knuckle whereby the nose thereof is exterior to said die and free to move relative 70 to said tail, means for applying pressure to said nose whereby the same is moved into its normal relation with said tail, means engageable with said tail upon application of pressure whereby said tail and hub are reshaped to conform with certain portions of the cavity of said die mem-

ber to correspond to similar parts of a new knuckle, and means engageable with said nose for reforming the same when said pressure is applied.

5 5. A knuckle reforming device comprising a base provided with a projecting die member, a die member pivoted to said base for receiving and reshaping the tail of said knuckle, said second die member having an opening adapted to receive said projecting die member, means for supporting said knuckle in said second die member whereby the nose thereof is exterior to the same, means for normally maintaining said projecting die member in spaced relation to said tail, and means for applying pressure to said nose to move the same into its normal relation with said tail and to effect an engagement between said projecting die member and said tail to reshape the same.

10 6. A knuckle reforming device comprising a base provided with a projecting die member, a die member pivoted to said base for receiving and reshaping the tail of said knuckle, said second die member having an opening adapted to receive said projecting die member, means for supporting said knuckle in said second die member whereby the nose thereof is exterior to the same, means for normally maintaining said projecting die member in spaced relation to said tail, means for applying pressure to said nose to move the same 15 into its normal relation with said tail and to effect an engagement between said projecting die member and said tail to reshape the same, and means engageable with said nose for reforming the same 20 when said pressure is applied.

25 7. A knuckle reforming device comprising a movable die member adapted to receive the hub and tail of said knuckle, means for supporting said knuckle in said die whereby said nose is free to move relative to said tail, means for applying pressure to said knuckle and to move the same and said die member whereby said nose is moved into its normal relation with said hub and tail to correspond to similar parts in a new knuckle, said die member having an opening, and means 30 extending into said opening and being engageable with said tail to reshape the same and said hub in conformity with certain portions of the cavity of said die member upon movement thereof to correspond to similar parts in a new knuckle.

35 8. The method of reforming a knuckle having a worn locking face and worn pulling faces, comprising the steps of heating said knuckle, bending said knuckle about the hub thereof to return certain of said pulling faces into substantially normal relation to said locking face corresponding to the disposition of similar faces in a new knuckle, and compressing said knuckle to return certain other of said pulling faces into substantially normal relation to the faces affected by said bending and to redistribute metal therein to reshape said worn faces to correspond to similar faces in a new knuckle.

40 9. In a method of reforming a knuckle having a nose portion having a worn pulling face and a tail portion having a worn locking face and projecting portions having worn faces, the steps of heating said knuckle, bending one of said first-named portions relative to the other to return said locking and pulling faces substantially into their normal relation corresponding to similar faces in a new knuckle, and compressing said tail portion to redistribute the metal therein to return the worn faces of said projecting portions into their normal 45 50 55 60 65 70 75 80 85 90 95 100 105 110 115 120 relation with the other of said faces corresponding to the normal relation of these faces in a new knuckle.

10. In a method of reforming a knuckle having a nose portion having a worn pulling face and a tail portion having a worn locking face and projecting portions having worn faces, the steps of heating said knuckle, bending one of said first-named portions relative to the other to return said locking and pulling faces substantially into their normal relation corresponding to similar faces in a new knuckle, and compressing said knuckle to reshape said locking and pulling faces and to redistribute the metal in said tail portion to return the worn faces of said projecting portions into their normal relation with the other of said faces corresponding to the normal relation of these faces in a new knuckle.

11. In a method of reforming a knuckle having a nose portion having a worn pulling face and a tail portion having a worn locking face and pulling lugs having worn faces, the steps of heating said knuckle, bending one of said first-named portions relative to the other to return said locking and pulling faces substantially into their normal relation corresponding to similar faces in a new knuckle, and compressing said tail portion to redistribute the metal therein to return the worn faces of said pulling lugs into their normal relation with the other of said faces corresponding to the normal relation of these faces in a new knuckle.

12. In a method of reforming a knuckle having a nose portion having a worn pulling face, a hub portion having a worn pivot pin opening and a tail portion having a worn locking face and projecting portions having worn faces, the steps of heating said knuckle, bending said nose portion relative to said tail portion about said hub portion to return said locking and pulling faces substantially into their normal relation corresponding to similar faces in a new knuckle, and compressing said knuckle to reshape said locking and pulling faces and to redistribute the metal in said tail portion to return the worn faces of said projecting portions into their normal relation with the other of said faces corresponding to the normal relation of these faces in a new knuckle, said bending and compressing returning said pivot pin

opening to its normal position in said hub and in its normal position in respect to said faces corresponding to similar parts in a new knuckle.

13. In a method of reforming a knuckle having a worn locking face and worn pulling faces, the steps of heating said knuckle, bending said knuckle to return certain of said pulling faces into substantially normal relation to said locking face corresponding to the disposition of similar faces in a new knuckle, and compressing said knuckle to redistribute metal therein to reshape said faces to correspond to similar faces in a new knuckle.

14. In a method of reforming a knuckle having a nose portion having a worn pulling face and a tail portion having a worn locking face, the steps of heating said knuckle, bending one of said first-named portions relative to the other to return said locking and pulling faces substantially into their normal relation corresponding to similar faces in a new knuckle, and compressing said knuckle to redistribute metal therein to reshape said faces to correspond to similar faces in a new knuckle.

15. In a method of reforming a knuckle having a nose portion having a worn pulling face and a tail portion having a worn locking face, the steps of heating said knuckle, bending one of said first-named portions relative to the other to return said locking and pulling faces substantially into their normal relation corresponding to similar faces in a new knuckle, and compressing said nose and tail to redistribute metal therein to reshape said faces to correspond to similar faces in a new knuckle.

16. In a method of reforming a knuckle having a nose portion having a worn pulling face and a tail having a worn locking face and projecting portions having worn faces, the steps of heating said knuckle, bending one of said first-named portions relative to the other to return said locking and pulling faces substantially into their normal relation corresponding to similar faces in a new knuckle, and compressing said knuckle to redistribute metal therein to return the worn faces of said pulling lugs into their normal relation with the other of said faces and to reshape all of said faces to correspond to similar faces in a new knuckle.

EDMUND P. KINNE.
